[57] CLAIM

The ornamental design for intercommunication apparatus without a handset, as shown.

DESCRIPTION

FIG. 1 is a top, front and right side perspective view of a intercommunication apparatus without a handset; FIG. 2 is a top, rear and right side perspective view thereof with a keyboard element thereof shifted to the right; and,

FIG. 3 is a bottom, left side and rear perspective view of the intercommunication apparatus thereof with the keyboard positioned as shown in FIG. 2.

The intercommunication apparatus includes a keyboard, a two-way microphone/loudspeaker, and a display on the microphone/loudspeaker. The keyboard is movable laterally of the two-way microphone/loudspeaker.

Fig. 1.

Fig. 2.
